VENTILATED BUFFING WHEEL

Elisha Winthrop Hall, Scituate, Mass.

Application August 9, 1935, Serial No. 35,498

7 Claims. (Cl. 51—193)

This invention relates to improvements in ventilated buffing wheels, and the object thereof is to provide a buffing wheel assembly having means for delivering currents of air from the central portion of the wheel outwardly to the periphery thereof during the revolution of the wheel.

In the use of buffing wheels for finishing and/or polishing articles the buffing wheel is rotated at a very high speed and the work forced against it by the operator with such pressure as may be required to produce the desired result. A suitable abradant or polishing material usually intermingled with a suitable carrying vehicle, such as a lubricant, usually is applied to the periphery of the wheel. The friction produced by the contact of the rapidly rotating periphery of the wheel with the work produces very considerable heat which in some instances is sufficient to char the fibres of the buffing material at the periphery of the wheel and in some instances will cause the material of the buffing wheel to burst into flames, as the buffing material is usually of cotton cloth or other combustible material.

I am aware that heretofore attempts have been made to provide means for cooling buffing wheels by circulation of air between the sections of the buffing wheels by mounting the buffing wheel sections upon a hollow shaft having a port or ports leading to the spaces between the sections of the buffing wheel, as disclosed in the patent to Zucker No. 1,573,961, but in such constructions the sections of the buffing wheel are so closely clamped together between collars upon the shaft that no sufficiently rapid circulation of air is permitted to accomplish the desired result.

I am also aware that the cooling of the wheel has been accomplished by means disclosed in the patent to Myers and Murray No. 1,922,108 in which the buffing wheel comprises a series of annular buffing units which are gathered at their inner edges to produce radially extending folds or ridges, the inner circumference of the annular buffing strips being held by a ring-shaped metal binding strip having toothed edges bent outwardly toward each other so as to clamp the layers of cloth together, the rings being also provided with lugs or projections which in the assembled wheel separates the units from each other. In this construction also the annular strips or layers of buffing material are provided at intervals with aligned apertures through which the air enters at a distance from the periphery of the buffing wheel and by virtue of the centrifugal

action is discharged between the sections at the periphery of the buffing wheel.

This construction is objectionable for several reasons. The apertures in the buffing material necessarily limit the extent of use of the buffing wheel as when it is worn down to the apertures the wheel can no longer be used to perform the buffing operation. Furthermore, the annular clamping rings are likely to be broken when the wheel is run at high speeds and when so broken will be projected outwardly with great force, thereby endangering the operator to serious injury.

The object of the present invention is to provide a ventilated buffing wheel which will avoid the defects inherent in such buffing wheels and which will permit a sufficiently free circulation thereof properly to cool the buffing wheel. This is accomplished in the present invention by providing a buffing wheel formed of a plurality of buffing units having hubs of rigid material provided with aligned apertures, with separator plates interposed between adjacent buffing units having slots communicating with said apertures and extending through the periphery of the separator plates operable when the wheel is rotated at a high speed to permit air to be drawn into the apertures in the hubs and to be ejected therefrom through the slots into the spaces between the adjacent units from which it escapes at the periphery of the wheel.

Preferred embodiments of the invention are illustrated in the accompanying drawing, in which,

Fig. 1 is an end view of the buffing wheel assembly showing the preferred form of separator plate, the arbor upon which the buffing wheel is mounted being shown in section;

Fig. 2 is a diametrical sectional view on line 2—2 Fig. 1 of the assembled buffing wheel shown in Fig. 1 including the clamping heads having apertures communicating with the apertures in the hubs of the buffing units, the arbor being shown in elevation;

Fig. 3 is a detail diametrical sectional view of one form of separator plates;

Fig. 4 is an enlarged detail sectional view on line 4—4 Fig. 1, showing the spheroidal distortions in the separator plate adapted to be embedded under pressure in the hub of an adjacent unit; and,

Fig. 5 is a similar view to Fig. 4 illustrating the use of a plurality of separator plates for spacing the buffing units more widely apart.

The buffing wheel illustrated in Figs. 1 and 2

- comprises a plurality, four being shown, of buffering units assembled upon an arbor with separator plates between adjacent units and all clamped together upon the arbor of the buffering machine.
- 5 Each of the buffering units comprises a cylindrical rigid hub 1 of any suitable thickness and any suitable material, such as fibreboard, wood, hardened plastic material, etc., having a central aperture which fits tightly upon the arbor 2 of the buffering machine.

10 The buffering material comprises a plurality of layers 3 of cloth which may be in the form of disks, but which preferably are bands gathered at their inner edges to fit upon the hub 1 and 15 which are firmly secured thereto in any desired manner. Preferably the layers of buffering material are gathered upon the hub in the manner disclosed in my copending application Serial Number 30,885, filed July 11, 1935, by providing 20 two annular bands of superimposed layers of cloth, the bands being united by overedge or jump stitching and gathered by a suitable tension, such as a wire encircling the lines of stitching, and drawing the same upon the hub or a 25 suitable mandrel, the layers of cloth being thereby brought into radial relation to the wheel, stitched together, and the tension member then removed.

30 The layers of buffering material are united by a preferably circular line of stitching 4 which extends through the layers of buffering material and through fibrous anchoring disks 5. Desirably the anchoring layers are secured to the hub by a circular line of stitching 6, and protective disks 7, 35 of canvas, are secured by a suitable adhesive to the anchoring disks 5. The hubs of the buffering units are provided with aligned apertures 8 which also extend through the anchoring and protective disks.

40 The buffering units thus constructed are assembled upon the arbor 2 with separator plates 9 interposed between the adjacent buffering units.

45 The buffering units thus assembled are clamped between suitable metallic heads or collars 10 and 11, the collar 10 preferably abutting against a shoulder 12 upon an enlarged portion of the shaft, the collar 11 being forced toward the collar 10 by a nut 13 mounted upon the screw threaded end of the shaft. The collars 10 and 11 are provided with apertures 14 and 15 which register with the apertures 8 in the hubs of the buffering 50 wheels.

55 The separator plates may be of any desired thickness and of any suitable material. Preferably the separator plates are formed of thin tough steel, approximately $\frac{3}{16}$ " in thickness, and are provided with slots 16 which communicate at their inner ends with the apertures 8 in the buffering units and extend through the periphery of 60 the separator plates. The slots in the separator plates desirably extend radially with respect to the axis of the buffering wheel in order to minimize the weakening of the separator plates.

65 In the operation of the buffering wheel, when run at high speed, air is drawn freely through the apertures 14 and 15 of the hub into the apertures in the hubs of the buffering disks and is thrown therefrom by centrifugal force into the spaces 17 between the adjacent units of the buffering wheel. Inasmuch as the gathering of the 70 layers of buffering material about the hub produces plaits 18 in the buffering material, some of which extend to the periphery of the buffering wheel and others of which extend in proximity thereto, and the outer layers of buffering material

75 of adjacent disks are separated by the anchoring layers, the protective layers, and the separator plates, relatively large spaces 17 are provided between the material of the adjacent buffering units at their inner peripheries, so that air is discharged from the spaces 17 through the periphery of the buffering wheel with sufficient rapidity to insure proper cooling of the buffering wheel when run at any speed, as the circulation of air naturally increases with the increase of centrifugal force due to the rapidity with which the buffering wheel is rotated.

In view of the fact that the operator at times presses the work more forcibly against certain units of the buffering wheel than others, means desirably are provided for preventing relative movement between the buffering wheel and the separator plates, so that the alinement of the apertures in the buffering wheel units and the separator plates may be maintained. To accomplish this purpose 20 the metal separator plates desirably are provided with means to interengage with the material of the hubs of one or more of the buffering units between which they are located. A convenient means, which is illustrated in Figs. 4 and 5 of the drawing, 25 comprises a plurality of spheroidal distortions 19 which may be produced by punching the separator plate from one side to produce a spheroidal projection upon the other side which, when the buffering units and separator plates are assembled and forced together by the nut 13, will embed the projecting spheroidal portions in the hubs of the buffering units. Such projections may be caused to extend either from one side or both sides of the separator plate. Alternatively, teeth 30 may be punched from the separator plates in one or both directions to engage the hubs of adjacent buffering disks, or the plates may be scored, or otherwise provided with frictional surfaces to engage the hubs of the buffering disk.

35 Where the buffering wheel is to be rotated at very high speeds, and requires greater amount of cooling, a plurality of separator plates may be employed and placed side by side, as illustrated in Fig. 5, intermediate of the adjacent buffering units. 40 In such case the spheroidal projections 19 will nest with each other. If the spheroidally punched portions are the same in both plates, the adjacent faces of the plates will be slightly separated because the spheroidal portions of one plate will 45 not completely fit into the complementary cavity of the other, so that the plates will be slightly separated and therefore capable of permitting an increased circulation of air from the apertures 8 into the spaces 17 between adjacent buffering disks. 50

55 By reason therefore of the present invention a ventilated buffering wheel is produced which will provide a sufficient circulation of air between the buffering units to maintain the buffering material sufficiently cool to avoid charring or burning of 60 the buffering material irrespective of the speed at which the wheel revolves. The separator plates, if of metal, are of such rigid construction and so firmly anchored to the hubs of the buffering units that there is no likelihood of fracture or displacement. Inasmuch as the apertures through which the air enters the buffering units are located within the hubs of the units, the wheel may be used until it is worn down practically to the periphery of the clamping heads.

65 It will be understood that while the separator plates are herein described as preferably steel plates they may be made of any suitable material. Relative rotation between the buffering wheel units and the separator plates may be prevent- 70

ed in any desired manner to insure proper alignment of the apertures in the buffing units, with the slots in the separator plates, the slots in the separator plates may extend in any desired direction toward the periphery of the wheel. Any suitable material may be employed for the buffing units, whether gathered as above described, or not.

It will therefore be understood that various changes in material, construction and arrangement of parts may be made within the meaning and scope of the following claims.

Having thus described the invention, what is claimed as new, and desired to be secured by Letters Patent, is:

1. A ventilated buffing wheel formed of a plurality of assembled buffing units having hubs provided with alined apertures, a plurality of annular layers of buffing material fitting upon said hub and secured thereto, integral disks of rigid material forming separator plates interposed between adjacent buffing units having slots communicating with said alined apertures and extending therefrom through the periphery of said separator plates, and means for admitting air to said apertures.

2. A ventilated buffing wheel formed of a plurality of assembled buffing units having hubs of rigid material provided with alined apertures, a plurality of annular layers of buffing material gathered at their inner edges to fit the respective hubs and secured thereupon, thereby providing outwardly extending plates of buffing material, integral disks forming separator plates between adjacent buffing units of larger diameter than said hubs and having air passages coinciding with said alined apertures and establishing communication between said hub apertures and the spaces between the plates of said buffing units, and means for admitting air to said apertures.

3. A ventilated buffing wheel formed of a plurality of assembled buffing units having hubs of rigid material provided with alined apertures, a plurality of annular layers of fabric gathered at their inner edges fitting upon and secured to the respective hubs, solid circular metallic separator plates interposed between adjacent buffing units having slots communicating with said alined apertures and with the spaces between the outer fabric layers of adjacent buffing units, and clamping plates having apertures registering with the apertures in said hubs.

4. A ventilated buffing wheel formed of a plurality of assembled buffing units having hubs of rigid material provided with alined apertures, a plurality of annular layers of fabric gathered at their inner edges fitting upon and secured to the respective hubs, solid circular metallic separator

plates of larger diameter than said hubs interposed between adjacent buffing units having slots communicating with said alined apertures and with the spaces between the outer fabric layers of adjacent buffing units, and provided with means 5 engaging the material of said hubs acting to prevent relative movement between the separator plates and hubs of the buffing units, and clamping plates having apertures registering with the apertures in said hubs.

5. A ventilated buffing wheel formed of a plurality of assembled buffing units having hubs of rigid material provided with alined apertures, a plurality of separator plates interposed between each pair of adjacent buffing units provided with 15 registering slots leading radially from said hub apertures through the periphery of said separator plates, interengaging means upon each pair of separator plates acting to prevent relative movement therebetween and between separator plates 20 and the hubs of said buffing units, and means for admitting air to said apertures.

6. A ventilated buffing wheel formed of a plurality of buffing units having hubs of rigid material provided with alined apertures, flat metallic 25 separator plates having radial slots communicating with said apertures and extending through the periphery of said plates, each of said separator plates being provided with small spheroidal deformations, relatively thick solid circular metal 30 clamping plates engaging the faces of the outermost buffing units when placed upon an arbor and provided with apertures communicating with the apertures in said hubs and operable when clamped together thereon with the buffing units 35 therebetween to embed said spheroidal deformations in the material of the adjacent buffing unit hub.

7. A ventilated buffing wheel formed of a plurality of units each having a hub of rigid material and provided with a plurality of strips of textile material gathered at their inner edges to fit said hub, anchoring disks of larger diameter than said hub secured to said strips by a line of through-and-through stitching, protective disks 45 adhesively secured to said anchoring disks, the hubs of said series of units being provided with alined apertures, solid circular metal separator plates between adjacent buffing units having slots communicating with said apertures and extending through the periphery of said disks, an arbor upon which said disks are mounted, metal clamping plates upon said arbor having apertures registering with the apertures in said hubs, and means for forcing said clamping disks toward 55 each other to clamp the assembled buffing units therebetween.

ELISHA WINTHROP HALL.
